UNITED STATES PATENT OFFICE

JAQUES CAMILLE PASCHALI, OF CHICAGO, ILLINOIS, ASSIGNOR TO ADDRESSOGRAPH COMPANY, OF WILMINGTON, DELAWARE, A CORPORATION OF DELAWARE

PRINTING PLATE AND METHOD OF MAKING

Original application filed September 27, 1928, Serial No. 308,694. Divided and this application filed May 15, 1930. Serial No. 452,580.

This is a division of my application Serial No. 308,694, filed September 27, 1928.

The object of this invention is to provide a blank, and a novel method of making the same, into a printing plate having embossed printing characters and adapted to be removably engaged with retaining devices of a frame in association with other printing plates to provide a closely spaced printing form.

10 A further object is to provide a novel method for making a printing plate by scoring a plate blank oppositely on its front and back to provide panels and embossing printing characters on said panels and separating the panels and engaging them with retaining devices on a frame in proper form, spacing, and arrangement.

15 In the accompanying drawing illustrating the method comprising my invention,

20 Fig. 1 is a plan view of a printing plate blank scored to form panels;

Fig. 2 is an enlarged transverse sectional view on the line 2-2 of Fig. 1;

25 Fig. 3 is a similar sectional view with type characters embossed on the type panels;

Fig. 4 shows the panels of the embossed blank of Fig. 3 separated from each other; and

30 Fig. 5 is a front view of a printing device comprising a frame having retaining means with which the embossed type panels are engaged to provide a printing form.

Heretofore printing plate blanks have been 35 made of standard sizes for corresponding frames, and the type characters have been embossed on these plates in machines of the kind disclosed in Patents No. 921,600, patented May 11, 1909; No. 955,116, patented April 12, 1910, and No. 1,518,904, patented

40 December 9, 1924. These plates have generally been one-piece plates, each having one or more lines of type characters but generally sufficient lines to make a complete address 45 and often including the salutation. With such plates it is necessary to replace an entire plate whenever any change is to be made therein such, for example, as a street number change. It is possible to block out type

50 characters and emboss thereover, but this is

not a method which can always be practiced satisfactorily by those not especially skilled, and besides it requires considerable time. Also there is a considerable proportion of each plate left blank which represents so much waste in material and unnecessary weight, both of which are important considerations in large lists.

55 My invention provides a novel method for making printing plates having a single line, as shown in the drawing, or having a plurality of lines, each plate adapted to be detachably engaged with and held by retaining devices on the frame. The blank

15 for making the plate is made of suitable sheet material of a kind which will enable printing characters to be embossed thereon, and which is well known in the art. This blank may be of any size, and it is divided

50 into panels 16 by parallel scoring 17 on its face and 18 on its back. The score lines on

the back are opposite the score lines on the front; they are preferably V-shaped as shown in Fig. 2, and they cut into the blank to a

55 sufficient depth so that the panels may be easily separated by pressure of the fingers but are connected together so that the blank

60 can be handled without accidental separation of the panels. The margin panels 16' are of sufficient width to accommodate the

65 jaws which hold them in the embossing machine, and when the embossing operation

70 is completed they are broken off and discarded. The type panels 16 between the

75 margin panels 16' are narrow but of suitable width for the type characters so that the

80 embossed panels can be mounted on the frame in proper line spacing. It is found in practice that the type lines can be em-

85 bosSED on the blank, Fig. 7, in usual line

85 spacing and still leave enough material at

90 the margins of each type line panel for en-

95 gagement with the retaining device on the

95 frame. It is difficult to represent the exact

100 dimensions and proportions in the pen and

been found that the printing characters may be embossed in several lines on a scored plate and in close line spacing, and the type line panels may be separated and mounted in a frame in line spacing for addressing. It may be that the scoring permits the metal to flow more easily in the embossing operation without distorting or breaking the plate. However, this may be, I do know that type characters, upper and lower case, can be embossed in several lines, in proper type spacing and line spacing, and when the panels are separated on the score lines each panel has sufficient side margin for operative engagement with retaining devices on the frame, these devices being arranged in close line spacing or otherwise, as desired. The retaining devices are lips struck up from the frame 9 in pairs of rows. The lips 19 of the upper row of each pair are inclined downwardly, and the lips 20 of the lower row of each pair are inclined upwardly, Fig. 5, to provide an angular groove under each row of lips, discontinuous because of the spacing of the lips, to receive the top and bottom edges of the panel, and these edges may be tapered by reason of the scoring, as shown in Fig. 4, to more easily fit under the lips. The panel is light in weight, and it is only necessary to provide a slight edge engagement with the retaining lips to hold the panel on the frame. Thus it is possible to form the type characters close to the edges of the panels, because only a slight projection of the panel beyond the type is required for engagement with the retaining lips; and in the V-shaped form of scoring shown, which I prefer, the extremity of the beveled edge is sufficient to effect this engagement. It will be understood, of course, that in actual practice the blank is quite thin, and the scoring is necessarily small transversely, but it is sufficient to enable the panels to be readily separated without liability of distorting the panels. The lips permit the panels to be inserted endwise and the use of light gauge metal for the plate blank; the inclined lips, forming discontinuous guide grooves for engagement of the tapered edges of the panel, enable the panel to be readily inserted and removed from the retaining devices of the frame or to be adjusted to any desired position.

Whereas it has been customary heretofore to emboss an address or other form on a single printing plate, which leaves a considerable portion of the plate blank, representing waste material and unnecessary weight in the complete printing device, with my invention the panels may be embossed for their full length and divided as required after separation from other panels so that all, or substantially all, of each panel may be employed for embossing. The type panels may be adjusted to any desired position on the frame to pro-

vide for block or indented arrangement of the address, for example, and any type panel may be changed without disturbing the other panels and as often as desired. This construction permits piece work on addressing and maintaining a list of addresses, because it is obvious that a stock of certain parts of the address may be maintained, and may even be set up in the frame, for use as required. Thus, in the address illustrated in the drawings, the "Chicago, Ill." type panel and the "Dear Sir" type panel may be stock material, made up at the factory and supplied to the customer, or made up by the customer's operator at odd times; and such stock material may be kept in storage for use as required, or it may be set up in frames for use as required. When a printing device is to be discontinued for any reason, the name and street address type panels may be removed and destroyed, the frame and the city and salutation type line panels being preserved for future use. Thus the invention reduces the cost and expedites the work of maintaining a list.

I have shown and described a printing plate blank and method of using the same for making printing plates adapted for use in a frame forming a complete printing device in accordance with my original invention, but I do not limit this invention to this particular use or adaptation, and reserve the right to practice the invention in making printing plates of any other kind and for any other purpose within the scope of the following claims:

I claim:

1. A blank of suitable material in which printing characters may be embossed to form a printing plate, said blank having oppositely disposed score lines dividing the blank into one or more panels on which printing characters are embossed with the character impressions located close to the score lines, and a marginal panel adapted to be gripped by the jaws of the embossing machine for holding the type panel in position to have characters embossed therein.

2. A blank of suitable material in which printing characters may be embossed to form a printing plate, said blank having oppositely disposed score lines dividing the blank into a plurality of panels on which printing characters are embossed with the character impressions located close to the score lines, and a marginal panel at each side of the plurality of type panels, either of said marginal panels adapted to be gripped by the jaws of the embossing machine for holding the blank with a type panel in position to have characters embossed therein.

3. The method of making a printing plate which consists in providing a blank, scoring the blank in parallel lines on opposite sides with the lines on one side disposed opposite

the lines on the other side to form narrow type panels, embossing printing characters on the panels with the character impressions located close to the score lines, and then separating the panels on the score lines whereby a plurality of embossed panels may be closely assembled to form a printing form with close line spacing.

4. The method of making a printing plate which consists in providing a blank, scoring the blank in parallel lines on opposite sides with the lines on one side disposed opposite the lines on the other side to form narrow type panels, embossing printing characters on said panels with the character impressions located close to the beveled edges of the panel, and then separating the panels on the score lines.
